UNITED STATES PATENT OFFICE.

LOUIS BLESSING, OF JACKSON, MICHIGAN.

RAILWAY-TIE.

1,071,291.

Specification of Letters Patent.

Patented Aug. 26, 1913.

Application filed March 18, 1911. Serial No. 615,187.

To all whom it may concern:

Be it known that I, LOUIS BLESSING, a citizen of the United States of America, residing at Jackson, in the county of Jackson 5 and State of Michigan, have invented certain new and useful Improvements in Railway-Ties, of which the following is a specification, reference being had therein to the accompanying drawings.

10 This invention relates to railroad ties, and more especially to that class thereof which are made of concrete or cement, and in which metallic brace-rods and strengthening members are employed to give to the tie the desired rigidity, and it has for its object an improved organization of the strengthening members which latter are so distributed within the tie-body as to strengthen the same laterally as well as vertically, and also to give a "continuous" 15 brace-support thereto from one end to the other.

The invention has been clearly illustrated in the accompanying drawings, in which 20 similar characters denote similar parts, and in which—

Figure 1 represents a top view of a railroad tie embodying my invention; Fig. 2 is a longitudinal vertical section thereof on lines 2—2 and also 2'—2' of Fig. 1; Fig. 3 is a longitudinal section of a tie illustrating a modification.

Briefly stated, my present invention constitutes an improvement on that described 35 and claimed in United States Letters Patent No. 873,292 granted to me on December 10, 1907, and in which the body of the tie had embedded therein a series of overlapping loops of reinforcing members or wires.

40 In my present invention I employ comparatively rigid bars extending longitudinally of the tie substantially from end to end thereof, some of these bars being shaped into truss-like members. By the present 45 construction I am enabled to produce not only a stronger tie than before, and to save considerable weight of metal besides gaining in the labor required to set the tie members in the mold in which the plastic mass 50 is formed.

Referring to the drawings, the preferred form is illustrated in Figs. 1 and 2 in which the cement tie body is reinforced by three braces 10, 11, 12, which are preferably made of twisted square rods. Cushion plates for 55 supporting the rails may be employed if desired, and the other braces are bent or shaped to form tension-rod 10' having their seat *a* or rail-support directly below the rails (see Fig. 2) from which points 60 they rise so as to form in the longitudinal center of the tie a bridge or truss-support *b*. In order to preserve the stability of this brace member, as a whole, a straight rod as 10, 11 or 12 is disposed above the truss-rod, 65 and its ends are bent over, as at 14, so that they may act in conjunction with the outer ends of the rod 10' and hold the same against flattening or straightening out.

In Fig. 3 I have illustrated a modification of the structure, the only difference being the addition of a longitudinal tie rod 20, extending from end to end of the tie and across the arch points of the truss-rods 10' respectively.

75 It is to be understood that the number of the trusses, braces, and tie-rods may be varied, *ad libitum*, and also that bars or rods of different kinds may be employed in lieu of those shown and described, without departing from the spirit of the invention.

I claim:

A railroad tie of cement or the like, comprising a longitudinal tension rod bent to have its lowermost points directly beneath 85 the rail supporting portions and having its adjacent parts bent upwardly to form a truss between said portions, and an independent tie rod resting upon said truss-rod between the rail supports and having hook 90 ends directly hooked over and engaging the upturned ends of said truss-rod and in engagement therewith.

In testimony whereof I affix my signature in presence of two witnesses.

LOUIS BLESSING.
